Patented Sept. 20, 1921.

FIG. 1.

FIG. 2.

FIG. 3.

Inventor
Aaron T. Butler

By
J. Ramey Kelly
Attorney

UNITED STATES PATENT OFFICE.

AARON T. BUTLER, OF LINTON, INDIANA.

FILE PROTECTOR AND SHEATH.

1,391,458.

Specification of Letters Patent. Patented Sept. 20, 1921.

Application filed November 4, 1920. Serial No. 421,613.

To all whom it may concern:

Be it known that I, AARON T. BUTLER, citizen of the United States, residing at Linton, in the county of Greene and State of Indiana, have invented certain new and useful Improvements in File Protectors and Sheaths, of which the following is a specification.

This invention relates to improvements in file protectors and more particularly to a protector designed to keep the idle edge or side of the file free from dust, dirt and other foreign matter and which is readily removable and changeable from side to side of the file.

The main object of my invention is to provide means to protect the idle side of a file when the same is being used and at the same time permit the file to be quickly changed so that either side will be available for use by the operator.

A still further object of the invention is to provide an improved handle which in addition to facilitating manipulation of the file serves as a means to retain the protector in place.

Another object of the invention is to provide a sheath or holder for the reception of the file and protector.

Various other objects and advantages of my invention will become apparent during the continuance of the following description.

In the drawings:—

Figure 1 is a view in top plan of the improved protector with the file in position.

Fig. 2 is a view in side elevation showing the file in place in connection with the protector and the handle arranged on the file.

Fig. 3 is a view in bottom plan showing the entire device assembled.

Referring particularly to Fig. 1, 10 designates the body of the protector which is formed of metal and which has its longitudinal edges upturned to form flanges 11. The front end of the body portion 10 is also bent upwardly and turned inwardly as at 12 so as to form a socket for the reception of one end of the file. The portion 12 may be soldered or otherwise secured to the adjacent portion of the flanges 11.

At its rear end the body portion 10 extends slightly beyond the point at which the flanges 11 terminate and the corners of the

extended portion are bent upwardly to form lips 13 and an opening 14 therebetween for the reception of the shank of the file as will be hereinafter described.

When the file 15 is in position its forward end lies in a socket formed by the inturned portion 12 and the adjacent portion of the flanges 11 while the lips 13 bear against the shoulders 16 at the other end of the file and the shank 17 lies in the opening 14.

The handle portion 17 may be formed of wood or other suitable or desirable material, and is provided with a central longitudinal opening or socket 18 for the reception of the shank 17 of the file. Adjacent the mouth of the opening 18 the handle is provided with an extension 19 which when in place lies beneath the body portion 10 of the protector and firmly retains the same in position about the file 15. The extension is tapered toward the free end and the sides are slightly beveled as at 20 for the purpose that will presently appear.

The sheath 21 which receives the file and protector may be formed from a single sheet of material whose longitudinal edges are bent as at 22 and whose end portion is bent as at 23. The other end of the sheath remains open and adjacent this opening, the portions 22 are cut away as at 24 to form a substantially wedge shaped opening. Consequently when the file and protector are in place within the sheath, the extension 19 of the handle 17 fits the wedge-shaped opening, the beveled edges 20 of the extension overlying and firmly retaining the adjacent edges of the portions 22 of the sheath. This arrangement provides for a complete and compact structure.

Having thus fully described my invention what I claim as new and desire to secure by Letters Patent is:—

1. In a device of the character described, the combination with a file having a shank, a protector comprising a body portion having its longitudinal edges upturned to form flanges, one end of said body portion being upturned and bent inwardly to form a socket, the other end of said body being provided with upstanding lips in spaced relation to each other, said body portion being adapted to receive said file, said shank projecting between said lips, a handle portion having an opening to receive said shank, and means on

said handle portion engageable with said body portion to maintain said body portion in position about said file.

2. In a device of the character described
5 a file, a constricted shank at one end of said file providing shoulders at the adjacent end of said file, a body portion adapted to receive said file and cover one side thereof, longitudinal flanges formed at the longitudinal edges of said body portion of less height than the thickness of said file, a socket formed at one end of said body portion to receive the adjacent end of said file, upstanding lips formed at the other end of
10 said body portion and abutting the shoulders of said file adjacent said shank, a handle

portion having an opening to receive said shank, an extension on said body portion engaging the outer face of said body portion, said extension tapering toward its free end 20 and being beveled along its longitudinal edges toward its inner face, and a removable sheath adapted to receive said file and said body portion and including means to coöperate with the beveled edges of said extension 25 substantially as described.

In testimony whereof I affix my signature in presence of two witnesses.

AARON T. BUTLER.
